UNITED STATES PATENT OFFICE.

ANTHONY P. HINSKY, OF HOBOKEN, NEW JERSEY.

INSULATING-CONDUIT FOR ELECTRIC WIRES.

No. 864,167.

Specification of Letters Patent.

Patented Aug. 27, 1907.

Application filed December 3, 1906. Serial No. 345,984.

To all whom it may concern:

Be it known that I, ANTHONY P. HINSKY, a citizen of the United States, and residing at Hoboken, in the county of Hudson and State of New Jersey, have invented certain new and useful Improvements in Insulating-Conduits for Electric Wires, of which the following is a specification, such as will enable those skilled in the art to which it appertains to make and use the same.

10 This invention relates to conduits for electric wires, and the object thereof is to provide an improved device of this class through which an electric wire or wires may be passed in the usual manner and which will thoroughly cover and protect said wire or wires and at 15 the same time be more flexible and practical in use than other devices of this class as usually constructed.

The invention is fully disclosed in the following specification, of which the accompanying drawing forms a part, in which the separate parts of my improvement are designated by suitable reference characters in each of the views, and in which:—

Figure 1 is a side view of a fibrous tube which forms the inner part or core of my improved electrical conduit; Fig. 2 a similar view of the tube shown in Fig. 1 25 showing said tube corrugated or beaded transversely so as to render the conduit more flexible; Fig. 3 a longitudinal section of the complete conduit; and, Fig. 4 a transverse section or end view thereof.

In the practice of my invention, I provide a tube *a* 30 composed of paper pulp or similar material and preferably formed from a strip of pasteboard or thick heavy paper, and in the operation of forming the said tube it is corrugated or ribbed transversely or circumferentially as shown at *a*² in Fig. 2 so as to form corresponding 35 circumferential grooves, the inner surface of the tube being left smooth and even throughout. The tube *a*, corrugated or ribbed circumferentially as shown in Fig. 2, is provided with a fabric covering *b* of strong heavy fibrous material, and in practice, the tube *a* before the 40 fabric covering *b* is placed thereon is saturated and covered with a coating of insulating material, and after the fabric covering *b* is placed on said tube, said covering is also saturated with and covered by insulating material.

45 It will be understood that the insulating material thoroughly preserves and protects both the tube *a*

and the fabric covering *b* and renders the conduit impervious to water or other liquid substances.

The method of making my improved tubular conduit for electric wires is described in an application for 5 Letters Patent filed by me of equal date herewith, in which a machine for carrying said method into effect and for forming my improved conduit is shown and described.

The material employed for saturating and covering the tube *a* and for saturating and covering the fabric 55 covering *b* so as to render the same impervious to moisture and at the same time give the conduit insulating qualities may consist of any of the liquid compositions now used for this purpose, and the application and use of which are well known. A conduit of the class specified made as described, while possessing all the insulating qualities necessary, is also strong and durable and much more flexible than is ordinary with devices of this class as usually constructed, the flexible qualities being given by corrugating the inner tube *a* transversely 60 or circumferentially in the manner described.

In the process of making or forming the tube *a* and providing the outer surface thereof with circumferential corrugations or ribs and corresponding grooves, the inner surface of said tube is left smooth and even and the 70 result is that the conduit when finished is flexible and the inner walls thereof being smooth and even throughout, the process of passing wires or cables therethrough is not interfered with in any way. My invention is not limited to any particular method or means for making the circumferential corrugations or ribs and corresponding grooves in the outer surface of the tube and this may be done in any desired manner.

Having fully described my invention, what I claim as new and desire to secure by Letters Patent, is:— 80

A tubular conduit for electric wires composed of fibrous material and provided in its outer surface with circumferential corrugations or ribs and corresponding grooves, the inner walls of the tube being smooth and even throughout, the said tube of fibrous material being also provided with a 85 fibrous covering, and said tube and fibrous covering being saturated with insulating and preservative material.

In testimony that I claim the foregoing as my invention I have signed my name in presence of the subscribing witnesses this 30th day of November 1906.

ANTHONY P. HINSKY.
